(57) **CLAIM**

The ornamental design for a money clip, as shown and described.

DESCRIPTION

FIG. 1 is a perspective view showing the money clip of the present invention in a partially open position retaining currency shown in phantom lines;

FIG. 2 is a perspective view of the money clip of the present invention shown in an open position;

FIG. 3 is a top plan view thereof;

FIG. 4 is a side elevation view thereof;

FIG. 5 is a bottom plan view thereof;

FIG. 6 is a front elevation view thereof;

FIG. 7 is a rear elevation view thereof; and,

FIG. 8 is a perspective view showing the money clip of the present invention in its closed position holding currency shown in phantom.

The broken lines are for illustrative purposes only and form no part of the claimed design.
